UNITED STATES PATENT OFFICE.

JOHN BUTTIGIEG, OF ROCKFORD, ILLINOIS.

JEWELRY-CASE.

1,388,094.

Specification of Letters Patent. Patented Aug. 16, 1921.

Application filed November 29, 1919. Serial No. 341,361.

To all whom it may concern:

Be it known that I, JOHN BUTTIGIEG, a citizen of the United States, residing at Rockford, in the county of Winnebago and State of Illinois, have invented new and useful Improvements in Jewelry-Cases, of which the following is a specification.

This invention relates to a case for holding jewelry and the like and the principal object 10 of the invention is to provide a case which is made in the form of an egg and is covered with white kid to simulate the appearance of an egg.

Another object of the invention is to provide pads in the case, one of which is recessed to receive the article of jewelry, to prevent movement of the article in the case.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view of the case complete.

Fig. 2 is a view of the two parts of the case separated.

Fig. 3 is a cross section.

In these views 1 indicates the case which is formed of the two halves 2 and 3. The 35 two halves are preferably made of metal and this metal is covered by a covering 4, preferably of white kid. A strip 5 of paper or the like is placed around the edge of each half and the edge of the cover is folded 40 over the strip and is suitably secured to the inside of the parts. A ring 6 of paper or the like has a part secured to the edge of one half with its other part projecting above said edge so as to fit within the other half

and thus hold the two halves together. The 45 folded over part of the covering and the strip 5 act to frictionally engage the case and thus hold the two halves of the case in closed position. The lower half 3 is provided with a pad 7 of cotton or the like and this pad 50 is provided with a recess 8 to receive the article of jewelry. The half 2 is also provided with a pad 9 and the face of this pad is adapted to engage the projecting part of the article held in the recess and thus prevent 55 any movement of the article when the case is closed.

The recess 8 is made to receive the article for which the case is intended.

It will of course be understood that the 60 case may be made in the shape of other articles such as oranges and other fruit and in this case the kid covering would be colored to simulate the skin of the fruit which the device is intended to represent.

It is thought from the foregoing description that the advantages and novel features of my invention will be readily apparent.

I desire it to be understood that I may make changes in the construction and in the 70 combination and arrangement of the several parts, provided that such changes fall within the scope of the appended claim.

What I claim is:—

A device of the class described comprising 75 a case of egg-shape formed of two halves, a strip secured to the inner wall of each half adjacent its edge, a covering for each half having its edges folded over said strip and secured to the inner wall, a strip connected with one half and having a part projecting therefrom for engaging the other half, said strip engaging the folded over portion of the covering of each half and a pad 80 in each half, one pad having a recess therein. 75

In testimony whereof I affix my signature.

JOHN BUTTIGIEG.
